UNITED STATES PATENT OFFICE.

MARTIN RAYMAKER AND JAMES H. RAYMAKER, OF SHEBOYGAN, WISCONSIN.

ENGINE STOP MECHANISM.

1,014,669.

Specification of Letters Patent.

Patented Jan. 16, 1912.

Application filed December 27, 1910. Serial No. 599,306.

To all whom it may concern:

Be it known that we, MARTIN RAYMAKER and JAMES H. RAYMAKER, both citizens of the United States, and residents of Sheboygan, in the county of Sheboygan and State of Wisconsin, have invented certain new and useful Improvements in Engine Stop Mechanism; and we do hereby declare that the following is a full, clear, and exact description thereof.

Our invention consists in what is herein particularly set forth with reference to the accompanying drawings and pointed out in the claims of this specification, its main object being to provide simple, economical and efficient means for absolute electric control of a steam-engine to prevent speeding of the same beyond a predetermined limit, and incidentally to provide for immediate stopping of such engine from a distant point, an important detail of the invention being a specific form of stop-valve shown and described.

Figure 1 of the drawings represents a front elevation of a stop-valve casing and means in connection therewith for electric control of the valve therein, the preferred form of valve and the interior of the casing being shown by dotted lines; Fig. 2, a sectional view of the casing and said valve, the valve being illustrated by full and dotted lines in open and closed position respectively, and Fig. 3, a diagram illustrating an engine-driven generator, electrical resistance and a field-magnet in a constantly closed circuit, as well as means for cutting out said resistance, the closing of the aforesaid valve being dependent upon extraordinary strength of said magnet variously acquired as hereinafter more fully explained.

Referring by numerals to the drawings, 4 indicates a casing and 5 a rotary stop-valve therein, this valve being preferably of ogee form and centrally secured upon a stem 6. However we do not confine ourselves to any form of stop-valve or means for automatic closing of the same when released from its normally open position in the live-steam passage of an engine ahead 50 of an ordinary throttle-valve for the same passage.

The valve-stem 6 is shown as having its outer end fast in a lever 7, and this lever is provided with a nose 7'. The normal set 55 of the valve-lever is against the resistance of a spring 8 connected at its ends to the

said lever and a lug of the valve-casing. In this position of the valve-lever its nose 7' is in opposition to the preferably anti-friction roller end 9 of a detent 10 for which 60 a pivot 11 is provided on the front of the valve-casing. An angle-arm 10' of the detent is shown normally engaged by a hook 12 in connection with the armature 13 of a field-magnet 14 attached to the valve-casing, 65 the shank of the hook being guided in the magnet-frame and extended through a washer 15 over a spring 16 that is supported on said frame. Nuts 17 run on the hook-shank above the washer 14 serve to regulate 70 the tension-compression of the spring, and this spring resists the attraction of the armature by the field magnet. However any yielding resistance may be employed to resist attraction of the armature by said magnet under ordinary conditions. 75

The detent 10 is shown provided with a weight 10" designed to resist pull of the armature-hook 12, but it is obvious that a spring may be employed for the same purpose. 80

In practice the field-magnet 14 is in a constantly closed circuit with a generator 18 of electric current and this generator is run by the aforesaid engine, a resistance 85 grid or coil 19 being placed in said circuit between said magnet and generator to reduce the voltage of the line. Normally open switches may be employed at various points distant from the engine in connection with 90 parallel wires 20 and 21 connected to the positive wire of the aforesaid circuit on opposite sides of the resistance 19, a series of ordinary knife-type switches being shown in Fig. 3, as having their blades 22 swung 95 away from opposing contacts 23.

Ordinarily the electric resistance in the field-magnet circuit is such that the strength of the magnet is insufficient to attract the armature 13 against the yielding mechanical resistance aforesaid, but, if from any cause, the speed of the engine becomes excessive, the speed of the generator 18 will be correspondingly increased until such time as the electric-pressure on the magnet side 105 of the resistance 19 is sufficient to energize said magnet to a degree sufficient to overcome said mechanical resistance and thus attract said armature, the result being a tilt of the detent 10 by the hook 12 and a release of the lever 7 to permit contraction of 110 the spring 8, whereby there is automatic

shift of the stop-valve from open to closed position and immediate stopping of the engine. The velocity of the steam acting against the preferred form of stop-valve aids the closing operation of said valve. If any one of the aforesaid switches be closed to cut out the resistance 19 and permit full current strength of the generator 18 to energize the field magnet, the automatic closing of the stop-valve will be automatically effected in the manner above specified.

From the foregoing it will be readily understood, that it is impossible for the engine to run beyond a predetermined speed, and in case of accident at a point distant from said engine, the latter may be instantly stopped by the simple closing of a conveniently located electric switch. It is also to be observed that the control of the stop-valve to prevent excessive speeding of the engine is independent of ordinary governor-mechanism of said engine, the field-magnet and the armature thereof, under control of a yielding mechanical resistance, being virtually the governor, inasmuch as speed of the aforesaid engine is permissible up to a predetermined degree that will result in sufficient energization of said magnet to attract said armature from normal position to permit automatic closing of the stop-valve, said magnet being always in a closed circuit for an electric-current of variable voltage depending upon an engine-driven generator in the same circuit.

35 We claim:

1. The combination of an automatically closing steam-engine stop-valve, a field-magnet and an engine driven electric-generator in a constantly closed circuit with the magnet, the voltage of the line being variable in proportion to the speed of the engine; an armature opposing the magnet, a yielding mechanical resistance by which the armature is held away from said magnet when the energization of the same is of less than a predetermined degree, and an armature-controlled trip-mechanism by which the stop-valve is held in normally open position, said valve being freed when said armature is attracted to the aforesaid magnet against said resistance.

sition, said valve being freed when said armature is attracted to the aforesaid magnet against said resistance. 50

2. The combination of an automatically closing steam-engine valve, a field-magnet, electric resistance and an engine-driven electric-generator in a constantly closed circuit with the magnet, the voltage of the line being variable in proportion to the speed of the engine; an armature opposing the magnet, a yielding mechanical resistance by which the armature is held away from said magnet when the energization of the same is of less than a predetermined degree, and an armature-controlled trip-mechanism by which the stop-valve is held in normally open position, said valve being freed when 60 said armature is attracted to the aforesaid magnet against said resistance. 65

3. The combination of an automatically closing steam-engine valve, a field-magnet, electric resistance and an engine-driven electric-generator in a constantly closed circuit with the magnet, the voltage of the line being variable in proportion to the speed of the engine; an armature opposing the magnet, a yielding mechanical resistance by which the armature is held away from said magnet when the energization of the same is of less than a predetermined degree, means for cutting out said electric resistance at a point distant from said engine, and an armature-controlled trip-mechanism by which the stop-valve is held in normally open position, said valve being freed when said armature is attracted to the aforesaid magnet against said mechanical 85 resistance. 80

In testimony that we claim the foregoing we have hereunto set our hands at Sheboygan in the county of Sheboygan and State of Wisconsin in the presence of two witnesses. 90
